CLAIM

The ornamental design for a lid with jar, as shown and described.

DESCRIPTION

FIG. 1 is a perspective view of a lid with jar, shown exploded from one another, according to my new design; FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The even-dash broken lines in the drawings depict portions of the lid with jar that form no part of the claimed design. The bracket lines indicate the order of assembly and form no part thereof.
